UNITED STATES PATENT OFFICE.

WILLIAM L. GIBB, OF OCEAN CITY, NEW JERSEY.

SHEET-PILING.

No. 927,964.

Specification of Letters Patent.

Patented July 13, 1909.

Application filed December 2, 1908. Serial No. 465,705.

To all whom it may concern:

Be it known that I, WILLIAM L. GIBB, a citizen of the United States, residing at Ocean City, in the county of Cape May and 5 State of New Jersey, have invented certain new and useful Improvements in Sheet-Piling, of which the following is a specification.

My invention relates to improvements in sheet piling, the object of the invention being 10 to provide an improved construction of sheet pile composed of sheet metal plates riveted together and constituting a hollow water passage from its upper to its lower end, the lower end of the pile being open to permit 15 the escape of the water to displace the sand and allow the pile to sink.

A further object is to provide improvements of this character with tongue and groove formation permitting the piles to be 20 assembled in a tight wall.

With these and other objects in view the invention consists in certain novel features of construction, and combinations and arrangements of parts as will be more fully 25 hereinafter described and pointed out in the claims.

In the accompanying drawings, Figure 1, is a view in side elevation illustrating my improvements. Fig. 2, is a view in longitudinal cross section, and Fig. 3, is a view in horizontal cross section.

My improved pile, comprises in the main two plates 1, 1, of sheet metal bent as shown in Fig. 3, and secured together by rivets 2. 35 It will be seen that throughout the greater portion of the width of the pile the sheets 1, 1, are spaced apart forming a hollow chamber, the sides of which latter being tightly closed when the edges of the plates 40 1, 1, are bent inwardly and securely riveted. The edges of the plates 1, 1, at one edge of the pile are flared apart as shown at 3 forming a groove, and the edges of the sheets at the opposite edge of the pile are disposed 45 flatly against each other forming a tongue 4 to enter the groove of an adjacent pile to form a continuous wall.

The upper end of the pile is closed by a cap plate 5, of a shape to exactly fit the hollow pile, and provided with depending flanges 6, and rivets 7 are projected through the sides 1, 1, and through said flanges 6 to secure the cap in place.

An inlet opening 7 is provided in one side 55 plate 1 near the upper end of the pile and is

preferably strengthened by an internally screw threaded boss 8 to receive the pipe not shown, to connect the pile with the source of hydraulic pressure.

An angle bar 9 is secured to one side face 60 of the pile near its lower end and serves by its cam action against the ground to guide a newly inserted pile into close engagement with the pile previously driven.

A hook 10 is secured to one side of the pile 65 near its upper end to facilitate withdrawing the pile from the ground and to support the pile in position when it begins to enter the ground.

The lower end of the pile is open and in operation after the pile is inserted in position, 70 water under hydraulic pressure is admitted through inlet 7, and flows down through the pile, escaping at the lower end, displacing the sand and dirt and allowing the pile to 75 settle.

Various slight changes might be made in the general form and arrangement of parts described without departing from my invention, and hence I do not restrict myself to the 80 precise details set forth, but consider myself at liberty to make such changes and alterations as fairly fall within the spirit and scope of my invention.

Having thus described my invention what 85 I claim as new and desire to secure by Letters Patent is:

1. A pile adapted to be hydraulically driven, comprising two plates of sheet metal secured together throughout their longitudinal edges, the plates at one edge of the pile flared apart forming a groove, the plates at the other edge of the pile forming a tongue, a cap plate closing the upper end of the pile, flanges on said cap plate secured to the side 90 plates means for admitting water to the pile, and the lower end of the pile open, substantially throughout the width thereof, whereby the water may freely escape under the edges 95 of the pile.

2. A pile adapted to be hydraulically driven, comprising two plates of sheet metal secured together throughout their longitudinal edges, the plates at one edge of the pile flared apart forming a groove, and the plates 100 at the other edge of the pile disposed flatly together forming a tongue, a cap plate, depending flanges on the cap plate projecting between the pile plates and conforming in shape to the interior of the pile, rivets passing 105 110

through the pile plates and flanges, securing the cap plate in position and closing the upper end of the pile, means for admitting water to the pile, and the lower end of the pile 5 open, substantially throughout the width thereof, whereby the water may freely escape under the edges of the pile.

In testimony whereof I have signed my name to this specification in the presence of two subscribing witnesses.

WILLIAM L. GIBB.
